(72) Inventor: **Robert Campbell Clark**, Pleasant View, UT (US)*Primary Examiner* — Michael A Pratt
(74) *Attorney, Agent, or Firm* — Steven L. Nichols; Van Cott, Bagley, Cornwall & McCarthy P.C.(73) Assignee: **Specialized Tactical Systems**, Pleasant View, UT (US)**CLAIM**(***) Term: **14 Years**

The ornamental design for a light with firearm mounting bracket, as shown and described.

(21) Appl. No.: **29/433,075****DESCRIPTION**(22) Filed: **Sep. 25, 2012**

FIG. 1 is an isometric view from above and from the rear of the light. As seen in FIG. 1, the light includes a light body that is attached to and supported on a bracket.

(51) LOC (10) Cl. **22-01**

FIG. 2 is an isometric view from below and from the rear of the light.

(52) U.S. Cl.

FIG. 3 is a top elevational view of the light.

USPC **D22/108**

FIG. 4 is a bottom elevational view of the light.

(58) **Field of Classification Search**

FIG. 5 is a left side elevational view of the light.

USPC D22/100, 108, 109; D26/24-27, 38, 40,

FIG. 6 is a right side elevational view of the light.

D26/42, 46-47, 51, 60, 113, 118, 130-133,

FIG. 7 is rear elevational view of the light.

D26/136; 362/157-158, 183, 184, 190, 194,

FIG. 8 is front elevational view of the light; and,

362/195, 196, 197, 202-208; 42/123-124,

FIG. 9 is an isometric view of the light that shows the front of the light and also shows the light body in an alternative orientation with respect to the mounting bracket as compared to all the other views of the light. Although FIG. 9 shows the light body rotationally oriented with respect to the mounting bracket at a particular angle, the view of FIG. 9 is not meant to be limiting as to the angles at which the light body may be orientated with respect to the mounting bracket.

42/127, 131-132, 146

The broken line showing aspects of the light with firearm mounting bracket in FIGS. 2, 4, 7 and 8 is included for the purpose of illustrating environment and forms no part of the claimed design.

See application file for complete search history.
